JEWEL CASE

Kenneth G. Niblack, 395 Linwood Ave.,
Buffalo, N.Y. 14209

Filed Oct. 1, 1968, Ser. No. 13,825

Term of patent 14 years

Int. Cl. D3—99

U.S. Cl. D87—1

Fig. 1.

Fig. 2.

Fig. 3.

FIG. 1 is a top plan view of a jewel case showing my new design in fully open condition, the opposite side being similar except that the transparent disc with pockets is omitted;

FIG. 2 is a top perspective view thereof; and

FIG. 3 is a perspective view thereof in a closed condition.

I claim:

The ornamental design for a jewel case, as shown and described.
